[57] CLAIM

The ornamental design for a can opener, as shown and described.

DESCRIPTION

FIG. 1 is a front, top and left side perspective view of a can opener showing my new design;
FIG. 2 is a front elevational view thereof;
FIG. 3 is a rear elevational view thereof;
FIG. 4 is a top plan view thereof;
FIG. 5 is a left side elevational view, the right side elevational view being substantially a mirror image thereof; and
FIG. 6 is a bottom plan view thereof.
